CLAIM

The ornamental design for an electric toothbrush, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top view of the electric toothbrush showing my new design;

FIG. 2 is a left side view thereof;

FIG. 3 is a front view thereof;

FIG. 4 is a right side view thereof;

FIG. 5 is a perspective view thereof;

FIG. 6 is a back view thereof;

FIG. 7 is a bottom view thereof;

FIG. 8 is a top view of an alternate embodiment of the design shown in FIGS. 1-7;

FIG. 9 is a left side view of the alternate embodiment shown in FIG. 8;

FIG. 10 is a right side view of the alternate embodiment shown in FIG. 8;

FIG. 11 is a perspective view of the alternate embodiment shown in FIG. 8;

FIG. 12 is a front view of the alternate embodiment shown in FIG. 8;

FIG. 13 is a back view of the alternate embodiment shown in FIG. 8; and,

FIG. 14 is a bottom view of the alternate embodiment shown in FIG. 8.
